INVENTOR
Nicholas Zuck

BY
Harold R. Stonebraker,
his ATTORNEY

UNITED STATES PATENT OFFICE.

NICHOLAS ZUCK, OF ROCHESTER, NEW YORK.

COAT-FRONT STRUCTURE.

Application filed March 28, 1921. Serial No. 456,368.

To all whom it may concern:

Be it known that I, NICHOLAS ZUCK, a citizen of the United States of America, residing at Rochester, in the county of Monroe and State of New York, have invented 5 certain new and useful Improvements in Coat-Front Structures, of which the following is a specification.

My invention relates to a coat front structure and has for its purpose to provide a coat front which can be manufactured readily and economically, also affording a durable and pliable coat front that can be worked into the highest quality and most 15 stylish coats.

A further object of the invention is to afford a coat front with a lapel or front portion possessing sufficient stiffness to retain the shape that is given it when the coat is 20 made, and sufficient flexibility to permit the lapel to be given what is known in the trade as a soft roll, affording a graceful, stylishly appearing lapel which will hold its shape indefinitely.

25 The invention will be made more clear from the following detailed description, in conjunction with the accompanying drawings, the novel features being pointed out in the claims following the description.

30 In the drawings:

Figure 1 is a front elevation of a coat front constructed in accordance with one embodiment of the invention, and

35 Figure 2 is a sectional view on line 2—2 of Figure 1.

The coat front comprises, in general, a 40 canvas portion 1, a hair-cloth portion 2 and a felt portion 3, affording, when secured together, the body or side portion A of the coat front and the lapel or front portion B.

The hair-cloth portion 2 extends throughout the body portion A and the lapel portion B, and alone constitutes the latter. It is preferably a fine, closely woven hair-cloth, such as known in the trade as "Hymo" 45 and consisting of cotton or wool woven with mohair or Chinese hair. The hair-cloth is treated by immersing it in a cementitious solution, preferably of a waterproofing nature which is caused to thoroughly permeate 50 every portion of the hair-cloth. This is an important characteristic of this invention, since by thus treating the hair-cloth fabric,

I am enabled to obtain a soft, pliable lapel portion which will readily yield to any desirable shaping in working the garment, and yet possessing sufficient stiffness to cause it to hold the given shape indefinitely. By this method I can produce what is known as a soft roll lapel coat, that is more durable, more pleasing in appearance, and more efficient from every tailoring viewpoint than has ever been previously produced by any known methods.

The hair-cloth fabric 2 is secured to the 65 felt 3 preferably by pressure, and retained by the action of the cementitious substance with which the hair-cloth is impregnated. The hair-cloth and felt being thus secured together, in the form of a stock fabric, 70 which forms the subject matter of a pending application, they are cut out from a single pattern at one operation after which the canvas is attached by stitching in the usual manner. It will be understood that 75 the invention may be carried out in various other ways without departing from the fundamental principle of my improvement, which consists essentially of imparting stiffness to the lapel portion of a coat front by 80 treating the hair-cloth or other fabric with a cementitious stiffening or waterproofing substance, such processed fabric also preferably, but not necessarily, being formed integral with and constituting a portion of the 85 fabric which extends into and stiffens the body or side portion of the coat front. Where I employ the terms "hair-cloth" and "felt" throughout the description, I intend 90 to refer to and cover any stiffening material, or any padding material, as the case may be.

I claim:

A coat front structure consisting of a 95 piece of haidcloth fabric comprising integral body and lapel portions impregnated with a cementitious stiffening substance, the stiffened haicloth fabric alone constituting the lapel portion, and a layer of padding material extending over the body portion 100 and terminating at the lapel portion, said padding material being secured to the body portion by the cementitious substance.

In witness whereof, I have hereunto signed my name.

NICHOLAS ZUCK.
